(57) **CLAIM**

I claim the ornamental design for the article square tissue box cover, as shown and described.

DESCRIPTION

FIG. 1 is a perspective view of one embodiment of a square tissue box cover illustrating my new design;

FIG. 2 is a top plan view thereof;

FIG. 3 is a bottom plan view thereof;

FIG. 4 is a left-side elevational view thereof, with the undisclosed right-side elevational view being a mirror image of that illustrated;

FIG. 5 is a front elevational view thereof with the undisclosed rear elevational view being identical to that illustrated;

FIG. 6 is a perspective view of an alternative embodiment of a square tissue box cover showing my new design;

FIG. 7 is a perspective view of another alternative embodiment of a square tissue box cover showing my new design; and,

FIG. 8 is a perspective view of a third alternative embodiment of a square tissue box cover showing my new design.
